UNITED STATES PATENT OFFICE

THEODORE R. TREIBER, OF CHICAGO, ILLINOIS

DESIGN FOR A BURIAL RECORD CONTAINER

Application filed May 14, 1931. Serial No. 39,854. Term of patent 7 years.

To all whom it may concern:

Be it known that I, THEODORE R. TREIBER, a citizen of the United States, residing at Chicago, in the county of Cook and State of Illinois, have invented a new, original, and ornamental Design for Burial Record Container, of which the following is a specification, reference being had to the accompanying drawing, forming a part hereof.

The drawing is a perspective view of a burial record container embodying my new design.

I claim:

The ornamental design for a burial record container as shown.

In witness hereof I hereunto affix my signature this 4th day of May, 1931.

THEODORE R. TREIBER.
